CLAIM

(57) The ornamental design for a mobile terminal, as shown and described.

DESCRIPTION

FIG. 1 is a perspective view of a mobile terminal;
FIG. 2 is a front view of the mobile terminal of FIG. 1;
FIG. 3 is a rear view of the mobile terminal of FIG. 1;
FIG. 4 is a left-side view of the mobile terminal of FIG. 1;
FIG. 5 is a right-side view of the mobile terminal of FIG. 1;
FIG. 6 is a top plan view of the mobile terminal of FIG. 1; and,
FIG. 7 is a bottom plan view of the mobile terminal of FIG. 1.
Symbols and/or images illustrated by evenly spaced broken lines at a bottom portion of the mobile terminal in FIGS. 1 and 2 form no part of the claimed design.
